UNITED STATES PATENT OFFICE.

GEORGE HAND SMITH, OF ROCHESTER, NEW YORK, ASSIGNOR TO SILAS O. SMITH, OF SAME PLACE.

IMPROVEMENT IN ILLUMINATION.

Specification forming part of Letters Patent No. 36,689, dated October 14, 1862.

To all whom it may concern:

Be it known that I, GEORGE HAND SMITH, of Rochester, in the county of Monroe and State of New York, have invented a new and Improved Method of Producing Light for the Various Purposes of Artificial Illumination; and I do hereby declare that the following is a full and exact description thereof, reference being had to the accompanying drawings and to the letters of reference marked thereon.

It is well known that a powerful light can be produced by directing jets of certain gases when in a state of combustion upon lime, magnesia, platina, and certain other substances. The incandescence of these substances in such cases is principally due to the high heat produced by the burning gases, and an intense light is the result.

A combined jet of oxygen and hydrogen gases, so arranged that they are brought in contact at the very moment of combustion, is the most effectual way of producing the heat necessary for the purpose above mentioned; but these two gases are somewhat expensive, and are procured with too much difficulty to become generally used for the purpose above mentioned.

Common illuminating-gas has been used instead of pure hydrogen for the production of light, upon the principle above described. This gas, being chiefly composed of carbureted hydrogen, is very effectual for this purpose, and when intermingled with a due proportion of oxygen it proves a very good substitute for the pure hydrogen.

In order to produce a complete combustion of the illuminating-gas in such cases, it should be mingled with a nearly equal portion of oxygen. These gases, while burned, should be directed upon a small quantity of lime, or other proper substance, in concentric jets, the oxygen being in the center. A high degree of incandescence is thus produced, and a proportionate amount of light, all of which is due to the degree of heat thus generated. Still the necessity exists of obtaining a supply of pure oxygen. An abundant supply of that gas exists in the atmosphere, but it is there mingled with about three times its weight of nitrogen—a gas which affords no aid to combustion. Hence it will require four times as

much air as of illuminating-gas in order to effect complete combustion. When common air is used for this purpose, therefore, three parts out of five are not only inert and useless, but these three parts being necessarily heated to a high degree, absorb and carry off a large portion of the heat generated by the combustion, and thus the lime is prevented from being heated sufficiently to produce any very intense degree of light.

My invention consists in a contrivance for overcoming this difficulty to such an extent that a jet of common air mingled with, or, as I prefer, placed concentrically within, a jet of illuminating-gas and forced upon a piece of lime at the moment of combustion will produce nearly the same result as though pure oxygen and hydrogen gases had been used for that purpose, and thus an intense degree of light can be produced from materials of the most common, cheap, and convenient character. To effect this purpose, I heat the common air by artificial means before it is used in the combustion of the illuminating-gas to such a degree as to compensate sufficiently for the loss of heat occasioned by the presence of the nitrogen. I find also that by thus preheating the common air the combustion of the illuminating-gas is much more rapid and complete than though the air was cold.

By reference to the drawings one method by which this result is obtained will readily be perceived.

A is a pipe which conveys the common air through the adjusting-cock S to its jet I, where it is to enter into combustion with the illuminating-gas.

X is the pipe conveying the illuminating-gas through its adjusting-cock P to its jet O, placed around the jet I. These two jets should be proportioned to the relative amount of gas they are respectively to convey.

F' (in dotted lines) is the jet of common air, which is discharged directly into the center of the burning jet of illuminating-gas F, (in dotted lines,) where its oxygen enters into combustion with the illuminating-gas, forming one jet of flame that impinges upon the piece of lime L, causing incandescence and producing the light desired.

B is a gas-burner, of wire-gauze, supplied

from the gas-pipe X at G, being regulated by the cock C. The flame of this burner heats the current of air passing through A before it passes to the jet I. The pipe A may be enlarged over the burner B, or divided into many tubes, or made into a coil for the purpose of more completely heating the air before it is forced into the flame. Two or more of these jets may be concentrated upon one piece of lime, according to the amount of light required. For most purposes four jets are preferred, standing ninety degrees apart from each other.

The heated air and gas might mix before reaching the jets; but I prefer the arrangement described in the drawings. There are also many other forms and methods in which the apparatus for heating common air can be arranged.

For greater economy, the waste heat from the combustion of the jets may be used, and contrivances for that purpose may readily be devised.

The arrangement of the burners and of the whole apparatus may be greatly changed without producing any change in the principle employed. I do not therefore intend to limit myself to any special contrivance or form of apparatus.

Other substances can be used as a combustible instead of illuminating-gas or hydrogen, such as olefiant gas or the hydrocarbons in vapor or in a liquid state, or any equivalent of these substances.

It may be observed that a moderate degree of heat applied to the common air will produce a sensible increase in the light produced, and that the greater the amount of heat applied to the air before combustion the more perfect will be that combustion, and especially will the heat and consequently the light produced be the greater.

The same contrivance for heating the common air to be used in connection with common illuminating-gas in a compound blow-pipe will be found equally efficient as that above pro-

posed for the generation of light, and upon precisely the same principle.

I have also ascertained that the light from oil or spirit lamps may be greatly increased by bringing a current of heated atmospheric air in contact with the flame, and for similar reasons to those above given.

Having thus fully described my invention and its mode of operation, it only remains to state that what I claim as new, and desire to secure by Letters Patent, is—

1. The use of common atmospheric air in the place of oxygen gas in the combustion of illuminating-gas or its equivalent, for the production of a high degree of heat, when such atmospheric air has been previously heated and in that condition is forced by means of properly-arranged jets into intimate contact with the illuminating-gas at the moment of combustion, substantially in the manner hereinabove set forth.

2. The use of common atmospheric air in the place of oxygen gas in the combustion of illuminating-gas or its equivalent for the production of an intense degree of light, when such atmospheric air has been previously heated, and in that condition is forced by properly-arranged jets into intimate contact with the illuminating-gas at or before the moment of combustion, both being at the same time made to impinge upon a suitable piece of lime or other known equivalent, substantially in the manner above described.

3. The use of common atmospheric air in the combustion of illuminating substances—such as illuminating-gas, oils, or hydrocarbons, or their equivalents—for the production of an increased degree of light, when such atmospheric air has been previously heated, and in that condition is brought in intimate contact with any of said illuminating substances at or before the moment of combustion.

GEORGE HAND SMITH.
